UNITED STATES PATENT OFFICE.

HARRISON H. ROUNTREE, OF CHICAGO, ILLINOIS.

DESIGN FOR A SPROCKET-WHEEL AND CHAIN GUARD.

SPECIFICATION forming part of Design No. 27,180, dated June 8, 1897.

Application filed April 23, 1897. Serial No. 633,543. Term of patent 3½ years.

To all whom it may concern:

Be it known that I, HARRISON H. ROUNTREE, a citizen of the United States, and a resident of Chicago, in the county of Cook, State of Illinois, have invented and produced a new and original Design for Sprocket-Wheel and Driving-Chain Guards for Bicycles, of which the following is a specification.

In the accompanying drawings, Figure 1 is a perspective view of a guard or shield embodying my design. Fig. 2 is a longitudinal section thereof on the line 2 2 of Fig. 1. Fig. 3 is a transverse sectional view thereof on the line 3 3 of Fig. 1.

A guard or shield of my design consists of a marginal frame A, having a flange A' projecting laterally therefrom, so that it will cover the driving sprocket and chain of a bicycle when properly secured to the frame - bars thereof.

At the front end of a guard or shield of my design is an opening which is defined by a

ring or annulus A², and extending forward from the rear end of said guard or shield is an opening, defined by substantially parallel bars A³. The ring or annulus A² and the bars A³ are connected with the marginal frame A by a web of open-work, consisting in part of bars a³, formed or molded to represent a lacing-cord, and in part of bars a², constituting an ornamental scroll, as shown.

I claim—

The design for a sprocket-wheel and driving-chain guard or shield for bicycles, substantially as herein shown and described.

In testimony that I claim the foregoing as my invention I hereunto set my hand, this 19th day of April, 1897, in the presence of two witnesses.

HARRISON H. ROUNTREE.

Witnesses:

B. DOUGLASS,
I. MEYER.
